UNITED STATES PATENT OFFICE.

LORENTZ LEHOTZKY, OF MCKEESPORT, PENNSYLVANIA.

RAIL-JOINT.

SPECIFICATION forming part of Letters Patent No. 729,946, dated June 2, 1903.

Application filed December 29, 1902. Serial No. 137,078. (No model.)

To all whom it may concern:

Be it known that I, LORENTZ LEHOTZKY, a citizen of the United States of America, residing at McKeesport, in the county of Allegheny 5 and State of Pennsylvania, have invented certain new and useful Improvements in Rail-Joints, of which the following is a specification, reference being had therein to the accompanying drawings.

This invention relates to certain new and useful improvements in rail-joints, the primary object of the invention being to provide a bolt for holding fish-plates to the webs of the rails, whereby to join two rails together without employing nuts, which are liable to become loosened from their bolts.

To this end the invention resides in the novel construction, combination, and arrangement of parts to be hereinafter more fully described, and specifically pointed out in the claims.

In describing the invention in detail reference is had to the accompanying drawings, forming a part of this specification, and where- 25 in like numerals of reference indicate like parts throughout the several views, in which—

Figure 1 is a detail perspective view of the abutting ends of rails joined together in accordance with my invention, one of the fish- 30 plates being partly broken away to show the form of aperture or opening in the web of the rail. Fig. 2 is a transverse vertical sectional view. Fig. 3 is a detached detail plan view of the locking-washer. Fig. 4 is a side elevation 35 of a part of the rail, showing one of the bolts in cross-section. Fig. 5 is a side elevation of a part of the rail, showing the bolt in position before the locking-lugs are turned down. Fig. 6 is a side elevation of a part of the rail, 40 showing the locking-lugs turned down, so as to prevent withdrawal of the bolt.

To put my invention into practice, I provide the rails 1 with openings 2 in the web and at each side of the openings provide slots 3, registering with the openings. The opening 2 is adapted to receive the shank 4 of the bolt, and the slots 3 are provided to permit the projecting sides or wings of the plate 5, formed integral with or rigidly secured to the 45 one end of the bolt, the other end of the bolt being provided with suitable head 6. The fish-plates 7 are provided with openings 8 and

with side slots 9, communicating with said openings, the openings 8 fitting the shank of the bolt and the side slots 9 permitting the locking-plate 5 to pass through beyond the 55 face of the fish-plates. After the bolts have been passed through the two fish-plates and webs of the rails they are held by means of the locking-washer 10, provided with a central opening 11 and side slots 12. The material cut away from these side slots is turned up to form lugs 14, extending at right angles to the face of the washer, and after the washer has been placed over the plate 5 it is turned 60 on the shank 4 of the bolt and the locking-lugs 14 are then pressed down flush with the face of the washer, so as to prevent the withdrawal of the bolt, even if the plate 5 is turned 65 so as to be in line with the openings in the washer in the fish-plate and rail.

To remove the bolts, the lugs 14 may be turned up, at which time the bolt can be readily withdrawn.

It will be noted that various changes may 75 be made in the details of construction without departing from the general spirit of my invention.

Having fully described my invention, what I claim as new, and desire to secure by Letters 80 Patent, is—

1. In a rail-joint, the combination with abutting rails having webs provided with bolt-openings, the webs of said rails being provided with longitudinally-arranged slots, and 85 fish-plates, of bolts provided with transversely-arranged locking-plates at one end, and heads at their opposite ends, and locking-washers provided with central bolt-openings and longitudinal slots communicating 90 with and extending from each side of the said openings, the said washers having integral lugs formed at the sides of the last-named slots, the said lugs adapted to be bent down flush with the said washers, substantially as 95 described.

2. In a rail-joint, the combination with abutting rails having webs provided with bolt-openings, the said webs provided with longitudinal slots communicating with and extending 100 from each side of the said openings, the said slots extending through the said webs, and fish-plates provided with bolt-openings and slots adapted to register with those of

the said webs, of bolts provided with transversely-arranged locking-plates at one end, and heads on their opposite ends, and locking-washers provided with central bolt-openings and longitudinal slots communicating with and extending from each side of the said openings, the said washers having integral lugs formed at the sides of the last-named slots, the said lugs adapted to be bent down

flush with the said washers, substantially as so described.

In testimony whereof I affix my signature in the presence of two witnesses.

LORENTZ LEHOTZKY.
